CLAIM

(51) **LOC (14) Cl.** **14-04**

The ornamental design for a display screen or portion thereof with graphical user interface, as shown and described.

(52) **U.S. Cl.** **D14/487**

DESCRIPTION

(58) **Field of Classification Search**

The FIGURE is a front view of a display screen or portion thereof with graphical user interface.

USPC ..... D14/485—495

The outermost broken lines in the FIGURE show a display screen or portion thereof, and form no part of the claimed design. All other broken lines show portions of the graphical user interface that form no part of the claimed design.
